Robert M. Orr.
ATTORNEY.

UNITED STATES PATENT OFFICE.

GEORGE E. ALLEN, OF PHILADELPHIA, PENNSYLVANIA.

FEED FOR THREAD WINDERS.

Application filed November 16, 1921. Serial No. 515,473.

To all whom it may concern:

Be it known that I, GEORGE E. ALLEN, a citizen of the United States, and a resident of Philadelphia, county of Philadelphia, 5 State of Pennsylvania, have invented certain new and useful Improvements in Feeds for Thread Winders, of which the following is a specification.

Some of the objects of the present invention are to provide an improved mechanism for winding thread or the like upon bobbins, spools, cops, or any other form upon which thread is to be built up; to provide a feeding device for thread winders wherein 10 the feeding operation ceases in case the thread breaks; to provide means for automatically varying the stroke limits of a thread guide as a bobbin is built up; to provide a feed guide, for thread winders, arranged to be controlled by the thread being wound; and to provide other improvements 15 as will hereinafter appear.

In the accompanying drawings, Fig. 1 represents a side elevation of a thread 20 winder embodying one form of the present invention, shown in connection with a bobbin during the winding operation; Fig. 2 represents a plan of the winding mechanism; Fig. 3 represents a rear elevation of 25 the winding mechanism; Fig. 4 represents a section on line 4—4 of Fig. 2; Fig. 5 represents a section on line 5—5 of Fig. 2; and Fig. 6 represents a plan of one form of cam for causing reciprocation of the winding 30 mechanism.

Referring to the drawings, one form of the present invention is illustrated in conjunction with a bobbin 10, which is of any standard or suitable form, arranged to rotate with a rotary spindle 11, which is journaled in and supported by a bearing bracket 12 rigidly secured to a rod 13 or other fixed part of the winding machine.

In order to rotate the bobbin 10 for winding purposes, the spindle 11 has a friction driven disc 14 fixed thereto and frictionally engaging the periphery of a friction drive wheel 15, which is fast to a shaft 16 driven from any suitable source of power.

For delivering the thread 20 to the bobbin 10 for winding purposes, an apertured or slotted guide 21, of earthenware, glass or other material permitting the thread 20 to run freely, is fixed to a rod 22 which is supported in operative position upon a movable carrier 23. Preferably this rod 22 is

of sufficient length to properly guide the thread 20 from the let-off spool (not shown) to a guide wheel or pulley 24, but is so spaced therefrom as to permit the thread 20 to be easily handled when placing it on the winding mechanism. The thread surface of the pulley 24, around which the thread 20 passes, is preferably grooved circumferentially so that the thread 20 is prevented from slipping or throwing off the pulley 24 during the winding operation. The pulley 24 is carried by a shaft 25 journaled in bearings 26 which form a part of the carrier 23.

In order to cause the thread 20 to travel longitudinally of the bobbin form 10 with the back and forth motion necessary for proper winding, the carriage 23 is arranged to be reciprocated by mounting it for free sliding movement upon a fixed feed screw 27, and providing a rigid extension 28 having a guide bearing 30, accurately fitted to a post 31 for sliding movement. The feed screw 27 and the post 31 are fast to a base 32 and extend vertically therefrom, in parallel relation, a distance sufficient to permit the carriage 23 to be given the required winding stroke for any bobbin form which is to be wound. The plate 32 is arranged to be removably mounted upon, or otherwise secured to, a transverse bar 33 suitably mounted as a reciprocatory part of the body of the machine and serving as a common mounting for a number of separate winding mechanisms if desired. Journalled to a bracket 34 upon the bar 33 is a cam roller 35 arranged to ride upon the cam face of a double end cam 36 which operates to give two reciprocations of the carriage 23 for each revolution of the cam 36. A shaft 37 carries the cam 36 and is driven by bevel gears 40 and 41 from the shaft 16, or in any other suitable manner for correct timing of the reciprocatory action.

As the winding of the bobbin 10 is built up it is necessary, in order to produce a cylindrical surface of uniform diameter, to provide means for shifting the stroke of the carriage 23 uniformly towards the top of the bobbin. This shifting takes place at each reciprocation and the amount of each shifting movement is substantially equal to the thickness or diameter of the thread being wound. In order to accomplish this step by step feeding of the carriage 23, a sleeve 42 is provided which fits freely over the feed screw

27 to slide thereon and is fastened to the carriage 23 by a bushing 43 and a collar 44 having set screws 45 engaging the said sleeve 42. The bushings 43 and 44 form 5 parts of the carriage 23 and are rigidly fastened in any well known manner. The end of the sleeve 42 is suitably shouldered to receive a star wheel 46 which is rotatably mounted upon the sleeve 42 and carries a 10 leader lug 47, formed of spring material, the end of which rides in the thread groove of the feed screw 27. Thus a turning movement of the star wheel 46 will cause the lug 47 to move longitudinally of the screw 27 and 15 thereby transmit the same movement to the sleeve 42 and the carriage 23.

For the purpose of turning the wheel 46 it is arranged in close proximity to and in overlapping relation with a worm gear 50 20 which is rotatably mounted upon a stud 51 bolted to the carriage 23, and in mesh with a worm 52 fast to the shaft 25. The gear 50 is provided with a plurality of tapped holes 53, all equally spaced radially from the axis 25 and arranged to receive threaded pins 54 which coat with the projection of the star wheel 46. In the present construction two such pins 54 are employed, these being located diametrically opposite to each other 30 to cause the star wheel 46 to move the distance of one tooth twice for each revolution of the gear 50 and thereby feeding the carriage 23 the required distance for accurate winding.

35 In connection with the foregoing construction it will be noted that the shaft 25 is driven by the pulley 24 from the thread 20 as it passes around the pulley 24 under the winding action of the bobbin 10. By this 40 construction the feeding movement of the carriage 23 is entirely dependent upon the thread 20, so that in case the thread 20 breaks, during a winding operation, the carriage 23 remains stationary until the 45 thread 20 is again connected and resumes winding. This insures resuming the winding at the same convolution of the bobbin winding where it stopped and results in a uniform building up of the bobbin with no 50 evidence of the aforesaid break. In winding mechanisms as heretofore constructed the feeding mechanism of the thread guide is controlled by means other than the thread, and in consequence if the thread breaks 55 the guide feed continues to operate while the thread is being connected again. The result is that the winding is resumed several convolutions beyond where it left off and the resulting wound bobbin has an 60 uneven and irregular appearance at the place or places where the thread had broken.

The operation of the winding mechanism is as follows: The thread 20 is initially secured to the bottom of the empty bobbin 10 and the machine is started to cause the shaft

16 to rotate to transmit motion to the bobbin 10. The frictional drive 14 and 15 permits the bobbin 10 to be removed, replaced or held while the thread is connected without stopping the shaft 16 by shutting down the 70 entire machine temporarily. With the bobbin 10 in motion the thread 20 is fed thereto and causes the pulley 24 to rotate while the cam 36 reciprocates the carriage 23 through a distance equal to one half the length of the 75 bobbin 10. The rotation of the pulley 24 causes the gear 50 to rotate and thereby bring the respective pins 54 intermittently into engagement with the star wheel 46, which is thus given a step-by-step motion 80 and advances the finger 47 along the threads of the feed screw 27. The carriage 23 is thus moved to change the limit positions of the thread stroke, and the parts are so arranged and proportioned as to advance 85 the said limits one convolution for each complete stroke or reciprocation of the carriage 23. Thus when the bobbin 10 is half wound the carriage 23 has moved along the feed screw 27 so that the lower limit of its movement is at the center of the length of the bobbin, while the upper limit of its movement is at the upper end of the bobbin. In this way the bobbin 10 is built up with an even 90 diameter for the required body portion and tapers off at the upper end in the usual manner. The superposed thread convolutions follow each other in regular sequence and in abutting relation so that the continuity of the winding is uninterrupted even 95 though there has been a breaking of the thread during the winding operation. When the bobbin is completely built up it can be removed and an empty bobbin form placed in its place to be wound. The thread winding mechanism is then brought to its initial 105 position by manually springing the finger 47 out of the thread of the screw 27 to thereby release the carriage 23 and its parts.

Having thus described my invention, I 110 claim:

1. In a winding mechanism, the combination of a guide for a thread, a bobbin arranged to cause said thread to be wound thereon, means for reciprocating said guide over a portion of said bobbin, and means spaced from said bobbin and driven by said thread for varying the position of said guide relative to said bobbin.

2. In a winding mechanism, the combination of a guide for a thread, a bobbin arranged to cause said thread to be wound thereon, means for reciprocating said guide over a portion of said bobbin, and means spaced from said bobbin and including a 120 step-by-step mechanism driven by said thread for varying the position of said guide relative to said bobbin.

3. In a winding mechanism, the combination of a guide for a thread, a bobbin ar- 130

ranged to cause said thread to be wound thereon, means for reciprocating said guide to cause said thread to move lengthwise of said bobbin while being wound, means for feeding said guide, and means spaced from said bobbin and driven by said thread for actuating said feeding means.

4. In a winding mechanism, the combination of a guide for a thread, a bobbin arranged to cause said thread to be wound thereon, a carriage supporting said guide, a feed screw connected to said carriage, means for reciprocating said feed screw, and means spaced from said bobbin and driven by said thread for moving said carriage and guide relative to said feed screw.

5. In a winding mechanism, the combination of a guide for a thread, a bobbin arranged to cause said thread to be wound thereon, a carriage supporting said guide, a feed screw connected to said carriage, means for reciprocating said feed screws, and means spaced from said bobbin and driven by said thread for intermittently moving said guide relative to said carriage.

6. In a winding mechanism, the combination of a guide for a thread, a bobbin arranged to cause said thread to be wound thereon, a carriage supporting said guide, a feed screw connected to said carriage, means for reciprocating said feed screw, and means spaced from said bobbin and including a step-by-step mechanism driven by said thread for intermittently moving said guide relative to said carriage.

7. In a winding mechanism, the combination of a guide for a thread, a bobbin arranged to cause said thread to be wound thereon, a carriage supporting said guide, a feed screw connected to said carriage, means for reciprocating said feed screw, and means spaced from said bobbin and including a feed screw and a step-by-step mechanism driven by said thread for intermittently moving said guide relative to said carriage.

8. In a winding mechanism, the combination of a bobbin arranged to cause a thread to be wound thereon, a support mounted for reciprocatory motion, a carriage mounted on said support and movable with respect to said support, means for moving said carriage relative to said support at predetermined intervals, and a rotatable element continuously driven by said thread to actuate said carriage moving means.

9. In a winding mechanism, the combination of a bobbin arranged to cause a thread to be wound thereon, a support mounted for reciprocatory motion, a carriage mounted on said support and movable with respect to said support, means for moving said carriage relative to said support at predetermined intervals, and thread driven means spaced from said bobbin for actuating said carriage moving means.

10. In a winding mechanism, the combination of a bobbin arranged to cause a thread to be wound thereon, a support mounted for reciprocatory motion, a carriage mounted on said support and movable with respect to said support, means for moving said carriage relative to said support at predetermined intervals, and thread driven means spaced from said bobbin and including a pulley for actuating said carriage moving means.

11. In a winding mechanism, the combination of a bobbin arranged to cause a thread to be wound thereon, a support mounted for reciprocatory motion, a carriage mounted on said support and movable with respect to said support, means for moving said carriage relative to said support at predetermined intervals, and thread driven means spaced from said bobbin and including a pulley and a step-by-step mechanism for actuating said carriage moving means.

Signed at Philadelphia, in the county of Philadelphia, and State of Pennsylvania, this 9th day of November, 1921.

GEORGE E. ALLEN.
